UNITED STATES PATENT OFFICE.

CHARLES B. CLARK, OF NEW YORK, N. Y.

AIR-ADMISSION DEVICE FOR LOCOMOTIVE FIRE-BOXES.

No. 813,862.

Specification of Letters Patent.

Patented Feb. 27, 1906

Application filed May 22, 1905. Serial No. 261,724.

To all whom it may concern:

Be it known that I, CHARLES B. CLARK, a citizen of the United States, and a resident of the city of New York, borough of the Bronx, in the county and State of New York, have invented a new and Improved Air-Admission Device for Locomotive Fire-Boxes, of which the following is a full, clear, and exact description.

This invention relates to air-admission devices for fuel-consuming structures; and it consists, substantially, in the details of construction and combinations of parts herein-after more particularly described, and pointed out in the claims.

The invention has reference more especially to air-admission devices for fire-boxes of locomotive-boilers, though equally applicable to furnaces and other fuel-consuming structures; and one of the principal objects thereof is to provide hand-controlled means whereby any desired quantities of atmospheric air may be conveniently introduced within the fire-box or other structure to effect a more complete burning or utilization of the gases arising from the fuel therein, thereby reducing to the minimum both the amount and density of smoke and other products of combustion passing to the smoke-stack or exit-flue.

A further object is to overcome numerous disadvantages and objections encountered in the use of many other contrivances hitherto devised for a similar purpose.

A still further object is to provide an air-admission device for fire-boxes of locomotive-boilers and the like, which is exceedingly simple in construction, easily controlled, and comparatively inexpensive to install, besides being thoroughly effective and reliable for its purpose and possessing the capacity for long and repeated service.

The above and additional objects are attained by means substantially such as are illustrated in the accompanying drawings, forming a part of this specification, in which similar characters of reference indicate corresponding parts in all the views.

Figure 1 is a front view of a fire-box or other fuel-consuming structure, provided with a door or closure having my improvements embodied in connection therewith. Fig. 2 is an inner perspective view of the door or closure for the fire-box, the air-admission device, *per se*, of my improvements being

omitted; and Fig. 3 is a vertical transverse sectional view taken on the line 3 3 of Fig. 1.

Before proceeding with a more detailed description it may be stated that in the form of my improvements herein shown I provide a specially-constructed door or closure for the usual fuel-opening in the front of a locomotive fire-box or other fuel-consuming structure, combined with which is a specially-constructed device for controlling the admission of atmospheric air to the interior of the fire-box, special means being also employed for securing the device in any of the positions to which it may be adjusted relatively to the door or closure, and while I have herein represented my improvements in a certain preferred embodiment it will be understood, of course, that I do not limit myself thereto in precise detail, since immaterial changes therein may be resorted to coming within the scope of my invention.

Reference being had to the drawings by the designating characters thereon, 1 represents the front of a locomotive fire-box, provided with the usual opening 2, through which coal or other fuel may be introduced within the fire-box, said opening being closed by means of a door or closure 3, having at corresponding corners thereof suitable members 4, uniting with similar members 5 on the said front 1 in the formation of a hinge for the door, which is completed by means of a rod or pin 6, extending through coinciding openings in each pair of said members referred to. The vertical edge of the door opposite that from which the hinge members 4 project is provided with a suitable catch 7, which may be engaged in any suitable manner for retaining the door or closure in closed position. The door or closure is provided with an opening 8, the sides of which are preferably rectangularly disposed, as shown, (see Fig. 2,) said opening resulting by severing a central portion of the door or closure on a horizontal line and bending rearwardly and inwardly the two portions 9 and 10 thus formed, which between them practically constitute a flue 11, through which atmospheric air may enter the fire-box from without, as will be apparent.

Hinged or otherwise movably supported at 12 on the face of the door or closure 3 is the upper longitudinal portion of an outwardly curved hood or member 13, having end sections 14, the inner edge 15 of each of which is straight and adapted to lie flatly against the

adjacent surface portions of the door or closure 3 whenever the said hood or member 13 is carried against the same. Secured to the face of the door or closure alongside of the 5 vertical sides of the opening 8 therein, by means of rivets or other suitable devices 16, are the flanges 17 of parallel forwardly-projecting members 18, preferably substantially triangular in form, said members bearing such 10 relation to the end sections 14 of the hood or member 13 as to constitute guides therefor, preventing endwise accidental dislocation of the hood or member from any cause either 15 when closed or when in an outward position of adjustment with reference to the air-admission opening 8 and flue 11. The said forwardly-projecting members 18 are provided at the inner lower edges thereof with corresponding spaced holes or openings 19, through 20 opposite ones of which is inserted or passed a rod 20 for sustaining the hood or member 13 in any desired outward position of adjustment thereof, as indicated in Fig. 3, and it is apparent that the greater the extent to 25 which the lower longitudinal edge of the said hood or member 13 is carried away from the face of the door or closure 3 the greater will be the amount of air admitted to the fire-box. Due to the proximity of the said hood or member 13 to the burning fuel within the fire-box 30 it is apparent that the same is caused to become very hot, and consequently the air passing beneath the same and into the fire-box will become highly heated previous to its entrance 35 into the latter, thus rendering the air in better condition to unite with the gases arising from the fuel within the fire-box in such manner as to effect a more complete burning or utilization of such gases and reducing in 40 great measure the amount of smoke and other products of combustion passing from the fire-box to the smoke-stack.

The hood or member 13 could in some instances be constructed of a simple flat plate; 45 but I prefer the curved form herein illustrated, together with the end sections 14 thereof, since due thereto quantities of heated air will continually be collected therein and operate in a measure as an aeroform 50 shield, preventing the material of the hood or member from rapid deterioration from the heat from the fire-box.

For convenient manipulation of the hood or member 13 the same is preferably provided at the lower edge thereof with a hand-grasp 21, and in order that the incoming air may be directed either downwardly or upwardly and within the fire-box I may bend the 55 inturned portions 9 and 10 of the door 3 either 60 upwardly or downwardly accordingly, as indicated in dotted lines in Fig. 3, for instance.

Having thus described my invention, I claim as new and desire to secure by Letters Patent—

65 1. An air-admission device for locomotive

fire-boxes comprising a closure for the fuel-opening therein, itself provided with an opening, an outwardly-swinging hood mounted on the face of the closure, and means for supporting the same in the different positions to which the lower edge thereof may be carried, embodying members having corresponding openings therein, and a device for insertion in opposite ones of said openings. 70

2. An air-admission device for locomotive fire-boxes comprising a closure for the fuel-opening therein, itself provided with an opening, an outwardly-swinging hood mounted on the face of the closure, means 80 for supporting the same in the different positions to which the lower edge thereof may be carried, embodying forwardly-projecting members from the face of the closure having spaced openings therein, and a supporting- 85 rod for the closure for insertion in corresponding ones of the openings. 75

3. An air-admission device for locomotive fire-boxes comprising a closure for the fuel-opening therein, itself provided with an 90 opening, an outwardly-swinging hood mounted on the face of the closure, and means for supporting the same in the different positions to which the lower edge thereof may be carried, said hood being of outwardly-curved form and having end sections, and said means embodying forwardly-projecting members from the face of the closure 95 constituting guides for the hood. 100

4. An air-admission device for locomotive fire-boxes comprising a closure for the fuel-opening therein, itself provided with an opening, an outwardly-swinging hood mounted on the face of the closure, and means for supporting the same in the different positions to which the lower edge thereof may be carried, the opening in the said closure being formed by bending portions of the closure inwardly, and said portions between them constituting a flue for imparting direction to the air passing into the fire-box. 105

5. An air-admission device for locomotive fire-boxes comprising a closure for the fuel-opening therein, itself provided with an opening, an outwardly-swinging hood 115 mounted on the face of the closure, and means for supporting the same in the different positions to which the lower edge thereof may be carried, embodying forwardly-extending members having flanges lying against 120 the face of the closure at opposite edges of the opening therein, and rivets securing said flanges to said closure. 115

In testimony whereof I have signed my name to this specification in the presence of 125 two subscribing witnesses.

CHARLES B. CLARK.
